Frank H. Argersinger Inventor

By his Attorneys,

C. A. Snow & Co.

UNITED STATES PATENT OFFICE.

FRANK. H. ARGERSINGER, OF NEWKIRK MILLS, NEW YORK.

DESIGN FOR A GAME-BOARD.

SPECIFICATION forming part of Design No. 20,117, dated August 26, 1890.

Application filed April 28, 1890. Serial No. 349,826. Term of patent 3½ years.

To all whom it may concern:

Be it known that I, FRANK. H. ARGERSINGER, a citizen of the United States, residing at Newkirk Mills, in the county of Fulton and State 5 of New York, have invented a new and original Design for Game-Boards, of which the following is a specification.

My design, as shown, consists of a circular convex surface, having arranged within its 10 periphery the representation of a six-rayed star having circular depressions or recesses, one at the center and one near the apex of each ray, the body of the star being ornamented with six equilateral triangles.

15 In the drawings and in this specification like letters of reference indicate corresponding parts.

In the drawings, Figure 1 is a plan view of 20 my game-board, and Fig. 2 is a sectional view of the same.

Referring to the drawings, A is a circular base-board having a circular wall C.

D is a circular plate convex on its upper side. Upon the convex surface of D is the

representation of a six-rayed star E, having 25 the circular depressions or recesses e, one at its center and one near the apex of each ray of the star. Arranged about the center, forming the body of the star, with one of their equal sides forming a base for the triangle at 30 each ray, are six equilateral triangles.

It is obvious that the essence of my invention is a circular convex plate having recesses or depressions therein, said recesses being arranged in regular mathematical order with 35 reference to each other and to the plate.

Having thus fully described my invention, what I claim as new, and desire to secure by Letters Patent, is—

The design for a game-board, as herein 40 shown and described.

In testimony that I claim the foregoing as my own I have hereto affixed my signature in presence of two witnesses.

FRANK. H. ARGERSINGER.
